RELNA E. MEECE, OF DAHINDA, ILLINOIS.

BLOCK-FORMING MACHINE.

1,119,095.

Specification of Letters Patent.

Patented Dec. 1, 1914.

Application filed February 24, 1911. Serial No. 610,579.

To all whom it may concern:

Be it known that I, RELNA E. MEECE, a citizen of the United States, and resident of Dahinda, in the county of Knox and State of Illinois, have invented a new and useful 5 Block-Forming Machine, of which the following is a specification.

My invention relates primarily to machines or devices for forming blocks and the 10 like of plastic material, such as Portland cement and its complements, as sand, gravel, and water. It will be evident however (as the nature of the invention is more fully disclosed,) that its use is not restricted to this 15 single employment. Devices of this character are severally known as machines which are moved from the blocks, and machines from which the blocks are removed.

My invention relates more particularly to 20 devices of the first recited type.

The invention has particular relation to "continuous air-space" block-forming machines; however, it may be used for forming 25 also solid blocks, apertured blocks, and recessed blocks, as well as for corner-blocks, cap and window blocks, ornamental pieces, etc.

A main object is to so construct the device 30 that its elements may be moved directly away from the block, in order that the latter will not be jolted, jarred, broken, marred, or thrown from its proper and desired shape and configuration.

In this connection it is an object to dis- 35 pense with hinged casing-parts or members.

It is an object to so construct and by un- 40 essential changes to so modify the device that it may be readily changed from a large to a small block machine, or to a corner-block machine, or to an ornamental block machine.

One of the main objects is to provide an 45 adjustable core, whereby continuous-air-space blocks of selective lengths may be formed in a single casing, and without the employment of a plurality of cores.

It is an object to provide a novel means 50 for and manner of placing the reinforcing wires or bonds.

It is a further object to provide a machine 55 which is very light in weight, and which may therefore be lifted and locally transported without tiring the operator.

Another object is to provide adjustable 60 casing-handles for a purpose presently related.

Still another object is to provide a core which is in sections, or separable.

A special object is to provide against separation of the box while the block is in process of formation.

In this connection it may be stated that it is an object to utilize the core with which to accomplish the last recited object.

It is an object to provide a casing having a fixed core-element.

It is an object to so arrange the parts that the mixture will be excluded from the joints.

It is an object to so arrange the parts that great speed may be attained and that the manipulations may be performed without effort.

That the mechanism constituting the means for carrying out the above recited objects be durable, strong and not prone to disability or disorder is a prime requisite.

Minor objects will be in part obvious and in part pointed out.

The invention accordingly consists in the features of construction, combinations of elements, and in the selective arrangements and disposition of the parts for co-action, the scope of which will be pointed out in the appended claims.

In the accompanying drawings Figure 1 is a top-plan, showing a preferred exemplification of my improvements, the parts in positions for beginning to form a block and the reinforce wires or bonds in the positions they occupy in the finished block; Fig. 2, a plan view, indicating the manner of withdrawing the parts of the machine away from the block, which latter is also shown;

Fig. 3, a plan view, similar to Fig. 1, but illustrating the manner of forming a corner block; Fig. 4, an end elevation of the central section of the core; Fig. 5, a vertical, longitudinal, central sectional view of one of the end sections of the core; Fig. 6, a face elevation thereof; Fig. 7, an end elevation, the handles released; Fig. 8, a modification, an end elevation, illustrating the cap and sill machine type of machine; Fig. 9, a plan of the same, the core shown in extended position to form a sill; Fig. 10, a plan, showing the core in closed or contracted position, to form a cap; Fig. 11, an end detail, seen from the inside, of the sill and cap type of a sliding head; Fig. 12, an end detail of a face plate or molding which is employed in connection with the head shown in Fig. 11;

and Fig. 13, a front elevation, partly broken away, of the type shown in plan view in Fig. 1.

That side of the machine at which the operator stands shall be herein termed the front.

Referring to the drawings by numerals, the same one indicating the same part in the different figures of the drawing, 2 represents an L-shaped casting, the longer portion 3 of which comprises a side and the shorter portion 4 the head of a casing, 5 denotes the other casing member, its side and end portions being designated by 6 and 7 respectively. The side 3 of the smaller type of machine is provided at its inner and upper edge with a notch 8, for a purpose presently described. This notch may or may not be omitted in the sill and cap type. The side 3 is provided with cleats 9, in recesses in which is pivotally mounted a rod 10 on which the operating levers 17 are fixed by means of set screws 11. The side 6 is provided with like cleats 12, in recesses in which is fixed by means of set screws 13, a rod 14. The sides 3 and 6 are thickened near and at their midlengths, and are longitudinally grooved at 15 to provide channels for the rods 10 and 14. Set screws 16 limit the movement of the rod 10 and thus the movement of the levers 17. (Now see Figs. 7, 8, and 13.) Said levers are preferably bowed upwardly and at their inner ends are constricted. Handles 20 are slidably mounted on the reduced portion of the levers and are locked in the desired position by screws 21. Each handle has a locking-projection 22 which engages the rod 14. A wedge-clip 23 is fixed by a set-screw 24 on each end portion of said rod 14, to restrain the levers from outward movement which might be occasioned by tamping the material within the casing and thus causing outward pressure on the ends thereof.

45 The L-shaped casing-members 2 and 5 form, when assembled, a rectangular casing. The side portion 6 of the small or block type is somewhat narrower than the integral end portion 7 and its upper and lower edges 50 are beveled as shown best at 25, Figs. 7 and 13. A face-plate 26, provided on its rear surface with strips 27, (which may or may not be integral therewith,) the opposed faces of which strips are undercut, is slidably mounted on said portion 6, the grooves permitting it to be slid along on and to be removed from said side portion. A plurality of these plates is furnished with each machine, each of a different length. The 55 end portion 7 is apertured for the reception of a bolt 29 by means of which, and a nut 30, a core-butt 31 is fixed to said end. The end portion 4 is equipped in a similar way and by similar means with a like core-butt. 60 Being duplicates, it will be necessary to de-

scribe but one of these. Each core-butt is a casting comprising convergent side walls 32, a front or face 33, a lower projection 34^a, and a top 34 provided with a projection 38. A bead 35 extends throughout the 70 length of the upper edge of each side wall. The front is apertured for the reception of the bolt 29 and is provided with a recess 36 for its head. Transversely of the front are deep grooves 39 which at their median 75 portions are cupped to permit of ready placement of a bond or reinforce wire which may be suitably bent. At its upper median portion and extending from the upper wall to and through the front, each butt is provided with a dovetail recess 40.

41 is a hollow intermediate core member, tapered from top to bottom, its sides 43 preferably sinuous, and if desired may be provided with projections 42. Each end portion 44 is provided at its bottom with a groove 45 which engages the projection 34^a. A dovetail 46 projects from each end and engages the similarly shaped recess 40. United as above, the intermediate member 41 will prevent outward movement of the butt-members, and they, being fixed by the bolts 29 will restrain the casing parts from their tendency to longitudinal movement, caused by tamping. The projection 38 engages a 95 notch 47 in each end portion, 4 or 7, as the case may be. A suitable handle 48 is secured on the upper portion of the central core-member.

49 is a sliding head, provided with a 100 notch 50 for the reception, as will now be described, of a projection 38. The sliding head is used when it is desired to make a block shorter in length than the interior of the casing. (In this event, a short intermediate core-section is also employed.) The end portion 4 is provided with apertured bosses 51 which loosely receive rods 52, and said bosses are radially bored and threaded to receive set screws 53 by which the rods 105 may be locked after adjustment. The adjustable or sliding head is provided with internally recessed and threaded bosses 54 for the engagement of threads on the ends of the rods 52. The length of the block 110 having been predetermined, a face plate of the proper length is slid onto the side portion 6, an intermediate core section of proper length engaged with the core butts, and the right hand core butt with the sliding head. 115 The set-screws 53 are then tightened to engage the rods 52 and thereby restrain the head from longitudinal movement. If it be desired to make a block the full length of the interior of the casing, the adjustable 120 head is dispensed with.

To make a corner block, as shown in Fig. 3, one of the core butts is moved from the end and engaged with the recess 8 in the side portion 2, the bolt 29 and nut 30 being 130

also shifted. In this instance a rockfaced sliding head 55 is employed, and inasmuch as the division of the block is at one end and one side, a curved intermediate core-section is used, and the core-butt is not engaged with the sliding head. A solid block may be made by omitting the entire core. An open-end block may be constructed by dispensing with the intermediate core section, and a centrally apertured block by dispensing with the core butts. It will be evident that the character and type of blocks which may be made with this device are manifold.

In the modification shown best at Figs. 9 and 10 the casing is elongated and the inner face of the front side portion of the casing is plane and without the beveled and narrowed features of the device shown in the principal figures. This type of casing is especially for sill, cap, and step blocks, posts and the like. The handles are not shown in these figures. An ornamental face plate or molding 56, (see Figs. 9 and 12) provided on its edge and near its ends with cleats 57 which constitute hand pieces by which it may be grasped, is laid within and alongside the casing-side. A correspondingly-shaped false or adjustable head 59 (Fig. 11) is employed at one end of the casing to restrain the molding from inward movement before the mixture is placed therein.

In making a cap block (see Fig. 10) the molding is omitted, as, of course, is also the head 59, for which head an ordinary one is substituted. In forming a cap or a sill (or the like) of relatively great length, an extensible intermediate core section (Figs. 9 and 10) is employed. Except that one of its ends is provided with an opening (only inferentially shown) the body of this core is like the core section 41.

60 is a shaft which telescopes within the intermediate core section and which has a head 61 provided with a dovetail 62 for engagement with the dovetail recess in a core-butt and provided also with a recess adapted for engagement with the projection 34^a of said butt. Should it be desired to make a very short block in the cap and sill style of machine, the proper core may be substituted for the one just described, or the core entirely dispensed with, the rods being lengthened by the employment of additional sections united after the ordinary fashion of pipes or rods—by a nipple.

The operation: The operator will assemble the machine parts as shown at Fig. 1, and will throw in a sufficient amount of material to fill the casing up to the level of or slightly above the lower pair 63 of bonds (Fig. 13) which may then be inserted through the transverse grooves in the core-butts and bent as desired. Being

ture, the wires will become firmly fixed therein, whereupon a sufficient quantity is added to fill the casing up to or slightly above the upper pair of transverse grooves in the core-butts. Tamping as above is then again resorted to, whereupon the upper pair 64 of bonds are placed and tamped into the aggregate. The casing is then filled to heaping, tamped, and smoothed off in the ordinary manner. Blocks then formed will not only be very strong, but the transverse portions of the bonds are so disposed with reference to the ends of the block that they provide a more facile and convenient means for grasping, for both local transportation and in laying them, than has heretofore been provided. As soon as the block has been completed the operator will release the levers from their engagement with the rod 14 and throw them to the upright position shown by Fig. 2, in which position they will be maintained by the set screws 16 contacting the casing side 3. He will then remove the intermediate core section by means of its handle. The casing section 2 is then drawn longitudinally, as indicated by the arrow *a*, whereby the core-butt secured to that section will be drawn in a straight line longitudinally of the block. As the face 95 of the side portion 3 is plane, it will slide freely over the rear face of the block, and without in the least disturbing it. Said section 2 is then moved rearwardly as indicated by the arrow *b*, and inasmuch as the first recited movement withdrew the core-butt entirely from the block, said butt will pass freely by the end of the block. The operator will then move the section 5 longitudinally, as indicated by the arrow 105 *c*, and thereby remove the core-butt from the end. The face plate 26 will, however, by reason of its adhesion to the moist mass, offer resistance, whereby it will remain in its original position, the side-portion sliding in the undercut grooves thereof. The face plate may then be released by drawing the section 5 in the direction indicated by the arrow *d*. To remove the large machine from the block, the operator will proceed with the core and with the casing section 2 as above described. In the event of the telescopic or extensible core section having been used the material above the shank is to be removed (by a trowel) before withdrawing said section. Section 5 will (after section 2 has been removed) be removed as above described. The attraction of the molding to the block will cause it to adhere thereto, but it may be readily removed 110 by sliding it lengthwise of the block, and this movement will cause a very smooth finish to be imparted to the face.

A completed block is shown at Fig. 2. It has not been thought necessary or best 130

to encumber this specification and drawings with additional descriptions and illustrations of modifications which are neither essential to nor form any part of the invention. In fact, it is apparent without such, that numerous changes may be made in the details of construction and by modifications involving only mechanical skill, without departing from the spirit and scope 10 of the invention.

Therefore, without limiting myself to particularities, except in certain of the claims which are for specific constructions, I claim as new the following, to wit:

- 15 1. A block-forming machine comprising a bottomless casing composed of a pair of separable, rectangular castings meeting at diagonal corners and adapted to be slid either longitudinally or laterally, a rod 20 pivotally secured in rear of the casing, means for limiting its rearward pivotal movement, levers secured on said rod, means for locking them thereon, a rod secured in front of the casing, clips thereon, means 25 for locking them thereon, said levers adapted for engagement with the latter rod and said clips, a head slideable within the casing, rods passing through the head of one of said casing members and removably 30 engaged with said slideable head, and a core removably disposed within the casing.
- 20 2. A block-forming machine comprising a bottomless casing composed of a pair of

separable L-shaped castings meeting at diagonal corners and adapted to be slid 35 either laterally or longitudinally, a rod pivotally secured in rear of the casing, levers secured on said rod, one at each end of the casing, a rod secured in front of the casing, slideable clips thereon, said levers 40 being adapted for engagement with said front rod and clips, a head slideable within the casing, rods passing through the head of one of the casing members and removably 45 engaged with said slideable head, and a core removably arranged within the casing.

- 25 3. In combination, a bottomless casing composed of a pair of separable L-shaped members meeting at diagonal corners, a rod 50 secured in rear of the casing, a rod parallel therewith and arranged in front of the casing, wedge like clips removably secured on the front rod, and levers secured on the rear rod and adapted to lock on the front 55 rod and to frictionally engage said clips whereby said levers are forced toward the ends of the casing.

In witness whereof, I hereunto affix my signature at Galesburg, Knox county, Illinois, this 13th day of February, 1911.

RELNA E. MEECE.
